A. S. McKEE.
AUTOMATIC SCALE.
APPLICATION FILED JAN. 10, 1920.

Patented Nov. 7, 1922.

UNITED STATES PATENT OFFICE.

AMOS S. MCKEE, OF CHICAGO, ILLINOIS.

AUTOMATIC SCALE.

Application filed January 10, 1920. Serial No. 350,509.

To all whom it may concern:

Be it known that I, AMOS S. MCKEE, a citizen of the United States, residing at Chicago, in the county of Cook and State of

5 Illinois, have invented certain new and useful Improvements in Automatic Scales, of which the following is a specification.

The invention relates to automatic weighing and filling devices.

10 One of the objects of the invention is to provide an improved device for automatically weighing mobile materials, such as liquids, and filling containers with admeasured, uniform quantities of such materials.

15 Another object is to provide an improved device for more accurately controlling the flow of mobile material or liquid by decreasing the stream flow before the predetermined quantity, by weight, has been de-

20 posited in a receptacle to be filled.

Another object is to provide a device which will entirely shut off the flow of material from a reservoir to a receptacle when the predetermined apportioned quantity 25 thereof has been deposited in the receptacle and which will automatically withdraw the filling nozzle from the filling position with respect to the receptacle.

Another object of the invention is to provide a device of the character described which will initiate a rather full flow of material into the receptacle until the receptacle has received a given quantity, and which will automatically decrease the flow 35 of material into the receptacle just prior to shutting it off entirely so as to more accurately weigh the material going into the receptacle.

Another object of the invention is to provide a filling nozzle, provided with a series of valve ports of different areas, connected to a reservoir containing liquid to be dispensed, and associating therewith a series of weight controlled stops for successively 45 arresting the nozzle with different ports open to diminish the flow by steps.

Other, further and more specific objects of the invention will become readily apparent to persons skilled in the art from a 50 consideration of the following description when taken in conjunction with the drawings, wherein:—

Fig. 1 is a diagrammatic representation of the apparatus, or device, with the parts in 55 position to begin the deposit of liquid into the receptacle.

Fig. 2 is a similar view, showing the parts in position after the smaller port has been connected to the reservoir, by the upward movement of the nozzle.

60

Fig. 3 shows the position of the parts when the nozzle has been moved into its extreme upper position and has closed the port communicating with the reservoir, and withdrawing the nozzle from the receptacle.

65

Fig. 4 is an enlarged section of the nozzle.

In all the views the same references characters are employed to indicate similar parts.

A reservoir, to contain the liquid to be deposited in receptacles, is indicated by the 70 reference character 5 and the receptacle by the character 6. The reservoir is connected to a nozzle casing 7 by a conduit 8. The nozzle 9 consists of a tube closed at its upper end and having, preferably, two ports, a larger port 75 10 and a smaller port 11, each adapted for registration with the open end of the conduit 8. When the parts are in positions shown in Fig. 1, the liquid, or other mobile material, will flow freely from the reservoir 80 5 through the conduit 8 and nozzle 9 into receptacle 6. When the parts are in position shown in Fig. 2, the port 11 will register with the open end in the conduit 8 and the flow will be proportionately restricted, 85 while in Fig. 3, the nozzle has been moved to its utmost upper position and has shut off the flow of liquid from the conduit 8 into the receptacle.

The apparatus to be hereinafter described, 90 accomplishes the operation of the mechanism to first cause the free flow of liquid into the receptacle, then to restrict the flow of liquid, so that the weighing apparatus will operate more accurately, and subsequently to 95 entirely shut off the flow of liquid into the receptacle; such operation being effectuated by the weight of the liquid deposited in the receptacle.

12 is a scale beam pivoted as at 13 to a 100 support 14, and having a table 14' supported on the end 15 of the scale beam, to receive and support the receptacle 6. Carried by the arm 15 are two contact levers, 16 and 17, pivoted thereto, as at 18 and 19, respectively. 105 These levers are insulated from the beam 15 and from each other and each serves as a member of a separate electric switch, operable by movement of the beam 15. A relatively stationary contact 20 cooperates with 110 the lever 16 and a similar contact 21 cooperates with the lever 17. Adjustable stops 22

and 23, carried by the beam 15, determine the time when the circuit is to be opened by the levers 16 and 17, with their respective contacts, 20 and 21. A spring 24 one for each lever, holds the lever yielding and normally in connection with the respective contacts 20 and 21. The arrangement is such, that when the beam 15 is depressed by the increased weight of the receptacle, the stop 22 removes the lever 16 away from its contact 20, thus opening an electric circuit before the circuit is opened by movement of the lever 17 from its stop 21. This is due to the fact that the stop 22 is located closer to its lever than is the stop 23 with respect to its lever, so that upon the downward movement of the end 15 of the beam, the circuit will be open first between the lever 16 and the contact 20 and subsequently upon further movement of the beam between the lever 17 and its contact 21.

A stop lever 25, is pivoted at 26, and has an end 27 movable into the path of the vertically movable nozzle 9. A weight 28 is attached to one end of a cord 29, which passes over a pair of pulleys 30 and 31 and is attached to the nozzle 9 as at 32. Weight 28 is sufficient at its other end to automatically lift the nozzle to its highest position, such as that shown in Fig. 3, when such movement is not opposed by the stops that may be placed within its path of movement.

When the stop 27 is in the position shown in Fig. 1, then the larger port 10, of the nozzle 9 registers with the opening of conduit 8, and a full flow of liquid from the reservoir to the receptacle is permissible. If the stop 27 be removed, then the weight 28 will move the nozzle upwardly to the stop lever 33, which is pivoted as at 32 and is provided with an extended end 35, that may be placed in the path of the ascending nozzle. When the stop lever 25 has been moved into the position shown in Fig. 2, then the weight 28 may move the nozzle up to the position shown in this figure, whereupon the restricted port 11 will register with the open end of the conduit 8 and a smaller flow of liquid will pass into the receptacle 6. Now if the stop 35 be removed from the path of the upwardly movable nozzle, then the weight 28 will move the nozzle into its extreme upper position in contact with a fixed stop 36, as shown in Fig. 3, whereupon the open end of the conduit 8 is closed and the lower end 9' of the nozzle has been raised above the receptacle 6 so that the receptacle may be readily removed from its position upon the weighing scale table.

An electromagnet 37, when energized, will hold the stop lever 25 in position shown in Fig. 1, and prevent weight 28 from raising nozzle 9. When, however, the circuit of the magnet is open, a weight 28 will raise nozzle 9 and thus move the stop lever out of the

path thereof into position shown in Fig. 2. Similar effects are produced when a magnet 38 is energized and when the circuit thereof is opened. Thus, magnet 38, when energized, holds stop 35 in the path of nozzle 9 and arrests the upward movement thereof. When, however, the magnet is deenergized weight 28 may elevate nozzle 9 against permanent stop 36.

An electric battery 40 is connected by a wire 41 to contact levers 16 and 17. The other terminal of the battery is connected by a wire 42 to the magnets 37 and 38, over the branch wires 43 and 44. A wire 45 connects the contact 20 to the other terminal 46 of the electromagnet 37, and the wire 47 connects the contact 21 to the other terminal 48 of the magnet 38. Now it will be manifest that, so long as the circuits are closed by the contact levers 16 and 17 and the respective contacts 20 and 21, magnets 37 and 38 will hold their respective stops 27 and 35 in the path of the ascending nozzle 9. After the magnets have been deenergized and the stops displaced by the upward movement of the nozzle, reenergizing of the magnets will not replace the stops. That must be done at the time when the nozzle is depressed, ready for action and in the particular instance, it is accomplished by manual operation.

One of the features of importance of the invention is the manner in which the scale beam 12 is poised. The shifting weight 50, on the beam 15, and a suspended weight 51 on the end 52 of the beam is not sufficient to correctly determine the weight of the liquid to be deposited in the receptacle 6. Another weight, 53, loosely connected to the lower end of the weight 51 is subsequently to be lifted by the upward movement of the beam end 52 as the receptacle becomes heavier.

The operation of the device is substantially as follows:—When the parts are in the positions shown in Fig. 3, the receptacle being placed upon the platform 14 of the scale, the outer ends 25 and 33 of the stop levers are then manually raised so that they are within the fields of the respective electromagnets 37 and 38. At that time there is no liquid in the receptacle 6 and the contacts 20 and 21 are closed, thus energizing the magnets. Before the stop levers are raised, however, the nozzle 9 is depressed into position shown in Fig. 1, causing the larger port 10 to register with the opening in the conduit 8, and causing the liquid to flow from the reservoir 5 into the receptacle 6. Instead of the liquid flowing downwardly in the receptacle, 6, I prefer to provide lateral openings 54 and to close the lower end of the nozzle, so that the liquid will flow into the receptacle from a lateral direction instead of vertical. This will not disturb the balancing effect of the scale. When the receptacle is put upon the

platform 14 and sufficient liquid is deposited in the receptacle, the outer end of the scale beam 52 will be raised by the depression of the inner end 15, by the accumulated weight 5 of the liquid within the receptacle. At this time the circuit is opened between the contact lever 16 and its contact 20, thus deenergizing the magnet 37, whereupon the nozzle will be raised and displace the end 27 10 that was previously in its path, and the weight 28 will lift the nozzle until it is in contact with the end 35 of the lever 33, as shown in Fig. 2. This operation will cause the smaller port 11 to be brought into register with the conduit 8 and the liquid will 15 flow in to the receptacle less rapidly. At this time, however, the weight 53 has not been lifted. Subsequent to the time that the outer end 52 of the scale beam lifts the 20 weight 53, the downward movement of the end 15 of the scale beam will move the contact lever 17 and open the circuit between it and its contact 21, thus deenergizing the magnet 38, whereupon the nozzle 9 will move 25 the stop 35 out of its path and it will be raised by weight 28 until it makes contact with the fixed stop 36, as clearly shown in Fig. 3, whereupon the nozzle will thereby close the port at the end of the conduit 8 30 and shut off the liquid and raise the lower end of the nozzle above the receptacle so that the latter may conveniently be removed from the scale platform.

The device, as described, is adapted for 35 use with any material that will flow, but is especially designed for filling receptacles with liquids of uniform aggregate weight. The effect of the weight 53 is to prevent the simultaneous de-energizing of both magnets 40 due to momentum of the scale beam.

While I have herein shown a single embodiment of my invention for the purpose of clear disclosure, it will be manifest to persons skilled in the art, that considerable 45 changes may be made in the arrangement and configuration of the parts within the scope of the appended claims.

Having described my invention, what I claim as new and desire to secure by Letters Patent, is:—

1. A liquid controller and weighing mechanism having in combinative association a scale beam to support the receptacle to be filled; a reservoir to contain the liquid for 55 deposit in said receptacle; a movable nozzle connected to the reservoir; a valve controlled by movement of the nozzle; a stop to hold the nozzle in filling position, with the valve open; means to move the nozzle out 60 of filling position to close the valve; and means operable by the scale beam to cause removal of the stop to permit movement of the nozzle.

2. An automatic scale providing a vertically movable tube having a plurality of

valve ports of different sizes and movable to be successively positioned between a source of supply of the material to be weighed and a receptacle for receiving the material, a movable scale beam, control mechanism successively operated through the movement of the beam to cause different valve ports to be positioned between the source and the receptacle, and means independent of the control mechanism and acting to increase the resistance of the beam after the same has moved through a portion of its travel.

3. A device of the character described having in combinative association a weighing scale member for supporting a receptacle to be filled; means to cause flow of material for deposit in said receptacle; a movable nozzle, serving as a part of a conduit for control of said material; means to move the nozzle from the receptacle; a stop in the path of the nozzle; an electro magnet, which, when energized, maintains the stop in said position; and means to open the circuit containing said magnet upon downward movement of the scale member to permit movement of said nozzle to stop the flow of material.

4. A device of the character described having in combinative association a weighing scale member with an insufficient initial resistance to its downward movement to indicate correctly the weight of a desired quantity of material to be deposited in a receptacle to be supported thereby; means to cause flow of material for deposit in said receptacle; a movable nozzle serving as a part of a conduit for control of flow of said material; means to move the nozzle from position to be occupied by the receptacle; a stop in the path of the nozzle; an electro-magnet, when energized to maintain the stop in said position; means to open the circuit containing said magnet, upon initial downward movement of the scale member, to permit movement of said nozzle whereby to decrease the flow of material; another stop in the path of said nozzle; an electro-magnet maintaining the latter stop in position; means to increase the resistance to movement of said scale member; and means to deenergize the second electro-magnet upon subsequent downward movement to the scale member, to permit further movement of the nozzle to stop the flow of said material.

5. A device of the character described having in combinative association a scale member movable by weight of an object supported thereon; a nozzle through which material may flow and movable with respect to the said member; a valve to restrict the flow of material through the nozzle and operable by movement of said nozzle; means normally preventing movement of the nozzle and operable through the initial downward movement of said scale member to open said valve; and means normally preventing fur-

- ther movement of the nozzle to close said valve and, upon the subsequent-downward movement of said scale member, permitting said valve to close.
5. 6. A device of the character described having in combinative association a scale member movable by weight of an object supported thereon; a nozzle through which material may flow and movable with respect to 10 said member; a valve to restrict the flow of material through the nozzle and operable by movement of said nozzle; stops for preventing movement of said nozzle; means to permit movement of said nozzle and operable by the initial downward movement of 15 said scale member; means to additionally restrain the movement of said scale member; and means to permit further movement of said nozzle to close said valve upon subsequent movement of the scale member after 20 the interposition of increased resistance to its movement.
7. An automatic weighing scale having a movable part provided with a plurality of valve ports of different sizes which may be successively positioned between a source of supply of a material and a receptacle for receiving the material and in which it is weighed, a scale beam for carrying the receptacle, electromagnetic means for controlling the movable part to effect the successive 25
- 30
- opening and closing the valve ports, and circuit connections controlled by the scale beam and governing the operation of the electromagnetic means.
8. An automatic weighing scale having a movable beam for supporting a receptacle for holding material being weighed, a movable nozzle for conveying material to the receptacle and having a plurality of openings of different sizes which may be brought successively into register with a conduit from a source of supply of the material, and means controlled by the beam for controlling the movement of the nozzle to control 40 the successive register of the openings therein.
9. An automatic weighing scale having a movable beam for supporting a receptacle for holding material being weighed, a movable nozzle for conveying material to the receptacle and having a plurality of openings of different sizes which may be brought successively into register with a conduit from a source of supply of the material, and electromagnetic means controlled by the beam for controlling the movement of the nozzle to control the successive register of 45 the openings therein.
- 50
- 55
- 60
- In testimony whereof I hereunto subscribed my name.

AMOS S. McKEE.
